UNITED STATES PATENT OFFICE

103,977

DESIGN FOR A ROTARY DISK EDGING MACHINE

Harry L. Myers, Toledo, Ohio, assignor to The
American Floor Surfacing Machine Company,
Toledo, Ohio, a corporation of Ohio

Application December 30, 1936, Serial No. 66,815

Term of patent 14 years

To all whom it may concern:

Be it known that I, Harry L. Myers, a citizen of the United States and resident of Toledo, county of Lucas, State of Ohio, have invented a new, original, and ornamental Design for a Rotary Disk Edging Machine, of which the following is a specification, reference being had to the accompanying drawings, forming a part thereof.

Fig. 1 is a front elevation of a rotary disk edging machine showing my new design; Fig. 2 is

a side elevation thereof; Fig. 3 is a rear elevation thereof, and Fig. 4 is a top plan view of the machine.

The dominant feature of my design resides in the top handle portion A of the machine.

I claim:

The ornamental design for a rotary disk edging machine, substantially as shown and described.

HARRY L. MYERS.
